DESIGN FOR A SHOE SOLE

Irving F. Starner, Belmont, Mass., assignor to The B. F. Goodrich Company, New York, N. Y., a corporation of New York

Application November 5, 1940, Serial No. 96,350

Term of patent 14 years

To all whom it may concern:

Be it known that I, Irving F. Starner, a citizen of the United States, residing at Belmont, in the county of Middlesex and Commonwealth of Massachusetts, have invented a new, original, and ornamental Design for a Shoe Sole, of which the following is a specification, reference being had to the accompanying drawing, forming a part thereof.

In the drawing:

Fig. 1 is a fragmentary plan view of a shoe sole embodying my new design.

Fig. 2 is a section taken along the line 2—2 of Fig. 1.

Fig. 3 is a section taken along the line 3—3 of Fig. 1.

Fig. 4 is a diagrammatic plan view on a reduced scale of the complete shoe sole.

I claim:

The ornamental design for a shoe sole, as shown.

IRVING F. STARNER.
